UNITED STATES PATENT OFFICE

2,005,038

VALUE STAMPING DEVICE

Márton Kálmán, Budapest, Hungary, assignor to
Universal Postal Frankers, Limited, London,
England, a corporation of Great Britain

Application July 18, 1930, Serial No. 468,929
In Great Britain July 19, 1929

23 Claims. (Cl. 101—91)

This invention is a novel improvement in machines whereby devices for printing values may be set to print any desired value or number up to a maximum capacity and may be adjusted by manually controlled setting up devices, and then printed either directly upon envelopes or upon strips or webs of paper, and the amount registered in the machine. In the particular embodiment of the machine illustrated in the drawings I have provided means whereby stamping or other indicia of any desired value up to the maximum may be set and printed upon an envelope, and/or also upon one or a plurality of strips or webs during each cycle of operations of the machine; and also the value of the stamp printed, at each operation, be also printed upon a record strip; and means are also provided whereby the value of each stamp printed is registered.

In such machine the printing devices are carried in a rotatable drum which has on its periphery a printing plate, which may be engraved with any suitable stamp, ticket, or other device which it is desired to print, and within this drum are arranged devices for printing any desired value in such stamp, also devices whereby a serial number may be printed in the stamp, also devices whereby any specific designation can be printed in such stamp; and also devices whereby the date may be printed in the stamp; all during each rotation of the drum. The machine also has means whereby the value of each stamp printed will be registered. It also has devices controlled by manually operable keys or levers which can be set in accordance with the value to be printed, and in such setting will operate mechanism whereby the value printing devices in the drum will be adjusted so that at the next succeeding operation of the drum this particular value will be printed in the stamp; and said setting up devices are such that during such printing operation of the drum the register will be operated by the set-up devices in accordance with the value of the stamp printed. The construction is such that the setting up devices will be disengaged from value printing devices in the drum prior to and during the rotation of the drum, and will be disconnected from the register when the drum is in normal position and the setting up devices are again operatively connected with the value printing devices in the drum. The machine also includes novel means whereby envelopes or the like may be fed past the drum to receive impressions therefrom at each operation of the stamp. Also novel devices whereby one or more duplicate

impressions may be taken from the printing devices on the drum during each rotation thereof on one or more strips or webs of paper for the purpose of providing record and voucher strips if desired. Also novel devices for printing the value only of each impression printed upon a record strip. The invention also provides means controlled by a meter or subtracting register whereby when the machine is used as a postage meter or franking machine the subtracting register can be set by the postal authorities for any amount of prepaid postage, and will then permit the machine to be used until the amount of prepaid postage is exhausted, whereupon the subtracting register will release devices which will prevent further effective operation of the machine until the meter is reset.

Among the novel minor features of the invention are means for preventing rotation of the drum while the setting up devices are being adjusted; means for preventing adjusting of the setting up devices while the drum is being operated to print; an ink reservoir in the drum; the means for presenting envelopes to the impression point; various devices for locking the machine when the total amount for which it has been set has been used; and various locking devices to prevent fraudulent operations of and tampering with the machine; also means whereby the operation of the machine may be coin controlled. Various other objects of the invention and novel features of construction will be hereinafter set forth.

I will describe the invention with reference to the accompanying drawings which illustrate one practical embodiment thereof, and various modifications; and an explanation and understanding thereof will enable others skilled in the art to adopt and use the invention. In the claims the essentials of the inventions and novel features of construction and novel combinations of parts for which protection is desired are summarized.

In the drawings:

Fig. 1 is a front view of the machine the casing removed and some parts broken away. Fig. 2 is a top view of Fig. 1. Fig. 3 is a left hand view of the machine with the casing removed and partly in section. Fig. 4 is an enlarged section of the printing drum on the line IV—IV of Fig. 2. Fig. 5 is a top view of the printing drum and its support detached. Fig. 6 is a front view of the print-drum. Fig. 7 is a section of the printing drum on the line VII—VII Fig. 5. Fig. 8 is a further enlarged sectional view of the drum showing the serial number and separate signs printing devices

- on the line VIII—VIII Fig. 4. Figs. 9, 10 and 11 are enlarged detail views of the device for adjusting and locking the value printing disks. Figs. 12, 13 and 14 are enlarged detail views of the devices 5 for manually operating the main shaft and for stopping same at each complete revolution thereof. Fig. 15 is a front view of part of the envelope guide table. Fig. 16 is a section of the device for raising the envelope guide table on the line 10 XVI—XVI of Fig. 15. Fig. 17 is a top view of the device for raising the envelope guide table. Fig. 18 is a side view of a modification of the envelope guide table. Figs. 19 and 20 are detail views of part of Fig. 18. Fig. 21 is an enlarged front view 15 of the mechanisms for taking impressions upon a plurality of strips or webs and for directing the strips or webs to and from the impression devices. Fig. 22 is a detail. Fig. 23 is a detail view of the mechanism shown in Fig. 21. Fig. 24 is a view of 20 one side of the setting up mechanisms. Fig. 25 is a section on the line XXV—XXV Fig. 24. Fig. 26 is a view from the left of the mechanism shown in Fig. 25. Fig. 27 is a view similar to Fig. 26 with disk 145 removed. Fig. 27a is a detail view of the 25 disk 150 detached. Fig. 28 is an enlarged diagrammatic view of the interlocking members of the setting up device, Fig. 25. Fig. 29 is a section on the line XXIX—XXIX Fig. 28. Fig. 30 is a top detail view of the tooth slide Figs. 28 and 29. 30 Fig. 31 is a front view of the receipt guiding table, enlarged. Fig. 32 is a top view thereof. Fig. 33 is an end view of Fig. 31. Fig. 34 is an enlarged detail view of the device for operating the shutter to prevent printing on an envelope. Fig. 35 is a 35 top view of Fig. 34. Fig. 36 is a front view of the complete machine. Fig. 37 is a top view thereof. Fig. 38 is a left hand end elevation thereof. Fig. 39 is a right hand elevation thereof.
- The main or drive shaft 1 is mounted in suitable 40 bearings 2, 3, 4, 5 attached to the base 13 (Figs. 1, 2, 3). This shaft may be rotated manually or by power as hereinafter explained.
- Disposed at right angles to shaft 1 is a shaft 10 mounted in bearings 11 and 12 on base 13 and on 45 this shaft 10 is fastened the printing drum 9 hereinafter explained. The shaft 10 is driven by and with the shaft 1 by means of intermeshing spiral gears 7 and 8.
- 50 *The printing drum 9*
- The printing drum 9 is shown enlarged in Figs. 4-8. In the construction shown this drum carries value or printing devices, serial number printing devices, special designation devices, and date 55 printing devices, which are preferably arranged within one quarter of the periphery of the drum, and are respectively indicated at 22, 23, 24 and 25 in Fig. 5. The drum carries on its surface a printing plate 21 which may consist of one or more curved pieces adapted to print any desired design or other matter which it is desired to have appear in connection with the other printing devices in the drum. The plate is provided with openings for the projection of the aforesaid printing devices 60 and the impression surfaces of the several printing devices projecting into said plate will be aligned with the surface of the plate so that an inclusive impression can be taken therefrom by means of suitable impression devices located at the periphery of the drum as hereinafter explained.
- 65 Within the drum opposite the opening 22, Fig. 5 are arranged printing numeral wheels 26 which are mounted rotatorily on a shaft 32, Fig. 7 supported between transverse walls 33 and 34, Fig. 75 4, the shaft 32 being disposed at right angles to
- the axis of the drum. Each wheel 26 has numerals 0 to 9 on its periphery and to each wheel 26 is attached a pinion 35 which is adapted to be engaged by one of the teeth of a comb 43 which is pivotally mounted at 42 between the walls 33, 33, 5 Fig. 4, and has an arm 41 that extends through an opening in the inner end wall of the drum (see Fig. 7) and carries a roller 45 engaging a cam member 46 attached to a bearing plate 11 in which the shaft 10 is journaled. This cam 46 10 through roller 45 will cause comb 43 to lock disk 35 and numeral wheels 26 in the positions in which they have been adjusted, during the rotation of the drum and until just before the latter reaches its position of rest, when the cam will 15 release the roller 45 and permit the spring 44, Fig. 7, to tilt the comb and disengage it from the pinions 35 and hold it so disengaged while the drum is in its position of rest.
- When the comb disengages the pinions 36 the 20 latter are engaged by pinions 201 under control of the setting mechanism, hereinafter explained, whereby while the drum is at rest the numeral wheels may be shifted to present the proper type at the periphery of the drum according to the 25 value of the stamp to be printed. But at no time can the numeral wheels 26 be shifted except by the setting up devices, as hereinafter explained.
- Serial number printing devices 30
- Within the drum 9 opposite the opening 23 therein, Figs. 5 and 8, is located a serial numbering device having numeral printing wheels 36 mounted on an axis 36a at right angles to the axis of the drum, the printing type on the 35 counter wheels projecting through the opening 23w in the printing plate 21 flush with the surface of said plate. These serial printing devices may be of any suitable construction and the specific construction thereof is not claimed herein. When desired it can be operated one point at each rotation of the drum to imprint the serial number on each impression by any suitable means. As shown it is actuated by a rod 48, Fig. 5 which projects through an opening in the 45 frame and is adapted to engage a cam 49 on the member 11 during each rotation of the drum and advance the counter one point. Its numeral wheels are locked by dogs 23n which, during the major portion of the rotation of the drum, are 50 held closed by means of a member 23x, Fig. 8 having a stem 23d, pivoted at 23c on the rear wall of the drum 9, and having a stud 23e engaging an annular ring 23f on the bearing plate 11, Figs. 5 and 8. This ring 23f extends concentric with 55 the axis of the drum but is broken at a point adjacent the cam 49 so that while passing this cam the counter will be shifted one point by the inward movement of rod 48 as above described.
- The cam 49 is preferably detachable or retractile so that when it is not desired to use the serial numbering mechanism this cam can be moved out of the way of the arm 48. Preferably cam 49 is slidably mounted in a holder 49x on the wheel 11. 60
- Specific designation printing devices 65
- Within the drum, and preferably beside the serial number printing device is a set of printing wheels 51 mounted on shaft 53 at right angles to the shaft of the drum. The respective wheels 51 may bear variable printing characters or designs which it may be desired to have appear upon the imprint in connection with the stamp engraved on the plate 21. Each wheel 51 has a 70
- 75

pinion 54 meshing with an intermediate 55 which in turn meshes with a pinion 56 on one of a nested series of shafts 57, see Figs. 4 and 8, each of shafts 57 carrying a disk 58 the periphery 5 of which projects through an opening 59 in the outer face of the drum (Figs. 6 and 8) so that it can be manually adjusted when the drum is at rest. By turning the disks 58 the related printing wheel 51 can be shifted to bring the desired 10 character thereon to printing position. Each pinion 56 has a notched hub or flange engaged by a spring actuated dog 61, Fig. 8 to hold the same yieldingly in adjusted position. Access can be had to the disks 58 for the purpose of adjusting same through an opening 387 in the casing, see Fig. 36.

The dating stamp

Also located within the drum is the usual dating stamp mechanism 25s (Fig. 5) the printing surfaces of which project through an opening 25 in plate 21 flush with the printing surface thereof. These dating stamps can be adjusted from the exterior of the drum; and access to these stamps for the purpose of setting same can be had through an opening in the casing closed by a bar 63, Figs. 36 and 37.

Ink supply

The printing drum shown also carries an ink supply or fountain which consists of a segmental holder 10 (Figs. 4, 5, 6) that can be inserted in the periphery of the drum and has its outer portion curved to correspond with the periphery of the drum. The arcuate side of this holder has an opening which is closed by a permeable cover preferably composed of an outer cloth 73 overlying a fine thread mattress cloth 74, which in turn overlies a felt layer 75, under which is a coarse cloth 76 of fabric or metal. The several layers may be secured together at their edges by a moisture proof binding 77, and inserted between the side walls 78 of the holder. When in position in the drum the arcuate cloth covered surface of the holder is outermost and forms a part of the periphery of the drum. Ink can be supplied to or drained from the holder through openings closed by plugs 71. As the holder rotates with the drum, the ink will be thoroughly shaken up and distributed and will permeate through the layers and be thinly distributed on the surface of the outermost layer 73. One filling of the holder with ink will maintain the ink supply for a much longer period than the ordinary exterior inking devices.

As the drum rotates the exterior surface of the fountain successively contacts with inking rollers 85 and 86 located at different points adjacent the peripheries of the drum, see Fig. 1, which rollers successively ink the printing surfaces on the drum prior to the impressions being taken therefrom, as hereinafter explained.

The envelope guide, etc.

Ordinary mail matter (which I will hereinafter designate by the inclusive term envelope) may be passed through the machine and printed by the indicia on the drum. The envelope is guided between a plate 121 (Fig. 1) and a yieldable table 60 or envelope support 98, which carries an impression roller 102, projecting slightly above the upper surface of the table at a point below the drum and adapted to press the envelope in contact with printing surfaces on the drum. The shaft of roller 102 is guided in slots 99 in the table and yieldably supported by spring 101, Fig. 15. The

table is tiltable on the pivots 109 supported as hereinafter described, and its inner end is normally pressed upward by a spring 103, Figs. 1 and 15, the extent of upward movement of the impression roller and inner end of the table being limited so the roller cannot contact with the drum. The upward movement of the inner end of the table may be regulated by any suitable means. As shown in Fig. 1 a chain or cable 105 is attached at 104 to the table and a screw 106 which 10 can be adjusted vertically by thumb nuts, as indicated in Fig. 1. This cable 105 limits the upward movement of the inner end of the table under action of spring 103, but permits the table to yield downwardly if necessary. Preferably the 15 pivots 109 are mounted on a yieldable plate 100 (Figs. 15-17) having depending members 108 slidably engaging guides 107 mounted on the base of the bed 14, Fig. 1. The plate 100 is guided in its vertical movement by vertical pins 113 telescoping 20 tubular studs 111 (Fig. 16) and springs 114 strung on pins 113 normally tend to raise the latter with the table 98. The upward movement of the table is limited by a ratchet member 115 attached to the plate 100, said member being engaged by a 25 dog 116 attached to an endwise movable shaft 118 mounted in the guides 107 (Figs. 15, 16) a spring 117 tends to push the dog 116 and rod 118 upward into engagement with the ratchet plate 115. Therefore if the table is forcibly depressed 30 against the action of the springs 114 it can be held in depressed position by the dog 116 engaging ratchet 115. The dog can be disengaged from the plate to permit the springs to raise the table by pushing rod 118 inward, said rod being provided with a button 119 for this purpose. The ratchet plate 115 is preferably provided with a wedge-shaped slot which is engaged by a tapered plug 129 on rod 118 when the latter is pushed inward, to prevent the springs 114 lifting the table 40 too violently and this plug being brought into frictional engagement with the slot in the ratchet 115 when the dog is pushed outward by the ratchet teeth as the table is lowered.

The envelopes are entered from the left, Fig. 1 between the plate 121 and the table 98. If an envelope be thick it will move the guide table 98 downward according to the thickness of the envelope, and the table will be automatically held in this adjusted position by the engagement of teeth 50 116 with ratchet 115 as above described. If it is desired to change the adjustment of the table the button 119 can be pushed inward to disengage the ratchet and allow the table to rise ready to be readjusted to suit thicker or thinner envelopes. 55

The impression roller 102 does not contact with the printing surfaces on the drum but the printing surfaces of the printing plate 21 and other printing members project beyond the periphery of the drum sufficiently to contact with the periphery of the impression roller 102 in its outermost position and therefore imprint a thin sheet of paper or card when the table is in its uppermost position. The insertion of an envelope fixes the position of the guiding table and it is unnecessary to again adjust the table for envelopes of similar thickness. The construction is such that the impression roller 102 will press the envelope into contact with the printing surfaces on the drum but the left hand or receiving end of the 60 table will not unduly bind the envelope between its upper surface and the plate 121 so that the envelope can pass freely through the machine and, after being printed, be discharged at the right hand end thereof, Fig. 1. The envelopes are delivered 70 75.

in the side of the bore and into an arcuate slot 152 in a disk 150 interposed between the gear 154 and the disk 145 (Fig. 25). The slot 152, in disk 150 (Fig. 27) has a cam portion 153 so that one 5 half of the slot 152 is nearer the axis of the disk than is the other half. Normally when the lever 156 is in normal or zero position the studs 149 on the slidable tooth 148 in disk 145 (Fig. 26) are entered in the inner portion of the slot 152 10 and the teeth 148 thereby retracted within the periphery of the disk 145; but if disk 150 is turned relative to disk 145 one or more of the pins 149 will ride up on the cam portion 153 of slot 152 into the higher portion thereof and one or more 15 of the teeth 148 will be successively projected through the disk 145 according to the extent of relative rotary movement of disks 150 and 145. There are as many toothed spaces in the opening 146 in disk 145 as there are numbers for printing 20 on the numeral wheels 26; and there is a like number of radially movable teeth 148 in the disk 145. When one or more teeth 148 of disk 145 are projected this disk becomes a spur wheel and such tooth actuates one or more registering devices which will be hereinafter explained.

The disk 150, Fig. 27, also has a radial slot 151 in which is slidably mounted a slide 159 having an upwardly directed tooth 157 on one side and a downwardly directed tooth 158 on the other 30 side. Tooth 158 projects into the groove 146 of a disk 145 and is adapted to be engaged with one of the notches between the teeth in the inner side of said notch. The tooth 157 projects into a slot in disk 154 and is adapted to engage in 35 one of the notches 154n in the upper side of the slot, see Fig. 28. Thus when the slide 159 is pushed up or outward the disk 154 is locked to the disk 150, but the disk 145 is free therefrom, but when the slide is lowered to inner position 40 the disk 150 will be locked to the disk 145 and the gear 154 will be disengaged. Preferably a spring 158a of any suitable kind may be arranged to normally hold slide 159 in its lower or inner position.

45 To disengage disk 150 from disk 145 and to engage disk 150 with the gear 154 the slide may be moved upward or outward by means of a radially movable member or pin 173 (Fig. 24) having a tappet 174 which is engaged by a slideable lever 163 slidably hung on the hub of disk 145 and retained thereon by a plate 165. Lever 163 is pivotally connected to a pivoted lever 167.

As stated to insure readily setting the adjusting levers 156 the top of the casing, Fig. 37, 50 should have proper numerals beside each of the slots 282 through which the levers project, so that by moving a lever 156 to the related numeral the proper number of teeth 148 in the related disk 145 will be projected. Each lever 156 is preferably provided with a spring pressed pin 288 mounted between lugs 284 and 285 on the arm (Fig. 3) and the inner ends of these pins are adapted to engage holes or notches in fixed arcuate plates 286. Each plate 286 is provided with 55 as many of these openings 287 for each of the numeral adjustments to which the related lever 156 is to be positioned. Only one of these openings 287 being shown in plates 286 in Fig. 2.

In the uppermost position of the rod 185 the 60 pins 173 on the disk 154, Figs. 24 and 25 will be moved inwardly by the springs 172, the levers 163 having been moved so as to permit this. On the upper end of each pin 173 is a tooth 288 which engages a notch 289 in the plate 286 when the 65 pin is moved inward and this holds the arms 156

and locks disk 154 in position. There are as many notches 289 for each position in which the related lever 156 is to be adjusted as there are perforations 287; but while only one row of notches 289 are shown in Fig. 2 when the gear 154 is 5 moved by swingable lever 156 it transmits motion first, as above described, to the value printing numeral wheels 26 in the drum, second to registers hereinafter explained which are so located that the number adjusted on said wheels will be 10 visible in openings 213 and 242 in the casing of the machine as indicated in Fig. 36.

The numeral disks 176a can be seen through slot 179 in the casing, Fig. 36, so that the operator can see that the desired number has been 15 set up by the levers. In practice the top of the casing of the machine would have rows of numerals adjacent each of the slots in which the levers 156 move, so that the operator can readily adjust the levers to set the machine for any desired 20 value amount.

To each pinion 178, Fig. 3 is attached a numeral printing disk 180 which serves the purpose of printing on a record ribbon or strip as herein-after explained and if desired these disks could 25 be seen from the back of the machine so that the number set up could be seen not only by the operator in the front of the machine but by a party standing at the back thereof.

Locks for the setting-up devices 30

On the shaft 1 is pivotally mounted a rock lever 183 (Fig. 3) one arm of which is pivotally connected to the lower end of manually depressible rod 185 having a hand piece 290 and normally held raised by expansible spring 186 interposed between the fixed member 187 and a collar on the rod 185. The other end of lever 183 has a pin 181 engaging a slot in a cam 184 fixed to the rock shaft 182 and on this rock shaft are 40 cams 181a respectively adapted to engage the free ends of a related lever 167 and move it upwardly, thereby causing said lever 167 to actuate the slide 159 as above described.

This rock shaft 182 also carries a cam 189 45 which when the shaft is rocked engages one end of the lever 190 pivotally mounted on shaft 1 and which lever is linked to a bar 190x Fig. 2 which is adapted to connect the swingable arm 192 and 193 carried by the shaft 200x. 50

When the arms 192 and 193 are swung upwardly the pinions 201 will be raised out of mesh with the pinion of the value printing wheels or disks 26 in the drum and simultaneously the pinions 194 will be drawn out of mesh with the pinions 196 of the numeral wheels 176a. In this position of the parts the value printing devices on the drum are no longer under the control of the setting devices and at such time the setting 55 devices will be locked against manipulation. 60

When the gears 201 are raised out of mesh with the pinion 35 of the printing wheels 26 the gears 201 will be engaged by a locking bar 205 on a lever 204. See Figs. 9 to 11, which bar 205 65 is yieldingly pressed down by spring 205s so that it will not injure the wheels, thus the pinions 201 are locked in position to re-engage the pinions 35 and are kept in position while engaged.

After the drum has made a complete revolution 70 and the value printing wheels 26 have been brought back to normal position the downward movement or lowering of arms 192 and 193 will lower the gears 201 meshing with the gears 36 and gear 194 meshing with the gears 176 and thus 75

again placing the value printing devices under the control of the setting up levers.

In order to insure the drum will be stopped in the exact position to enable the gear 201 to mesh with their respective gears 26 a wedge-shaped tooth 206 mounted on a spring 205a engages a wedge shaped recess 207 in the drum 9 (Figs. 9 and 11) at the end of each revolution thereof and insures the proper positioning of the drum.

The total register

In front of and adjacent the setting disks 154 and the operating levers 156 are arranged a total register T and a subtracting register S which are operated by the teeth 148 on the disks 145, after the latter have been projected by shifting the setting levers 156 and the disks then rotated by operating the main shaft 1. When so operated the projected teeth 148 of any disk 145 will engage a related spur wheel 246b on a shaft 246s supported in the frame of the registering mechanism.

The value stamp desired to be printed is determined by adjusting the levers 156 after the drum has reached its position of rest and the levers are released for operation. Then the lever 156 is shifted forward on the drum at the point 5. This will shift disk 154 correspondingly and through the mechanism above described cause the projection of five teeth 148 on related disk 145. Upon the next complete revolution of the main shaft the teeth 148 will as the shaft rotates engage the spur 246 and rotate the pinion 212 and transmit through intermediate pinion 221 and pinion 210 movements to the units disk carrying the latter through five points. Similarly if any other setting up levers are shifted the corresponding unit in the register say tens, hundreds or thousands, would be shifted in the manner above described upon the next succeeding rotation of the main shaft. For each revolution of the main shaft from position of rest to position of rest, the value set up by shifting any lever 156 will be correspondingly set up on the stamp and the amount thereof will be registered in the total register. Preferably the teeth 148 on the several disks 145 which will actuate the register units of successively higher value are disposed at different degrees relative to the axis of the shaft 1, so that during rotation of the shaft the teeth of the several disks 145 will come successively into operative engagement with their related registering units in the register, so that the units will be operated successively, for instance first the units, then the tens, then the hundreds and so on.

Upon the initial movement of the shaft 1 the shaft 200 and gears 194 are moved so as to disengage pinions 201 from the numeral wheels 26 in the drum, and also disengage gears 194 from the gears 176 of the printing or registering wheels 176a. Thus while the drum is performing its printing operations the projected teeth on the several disks successively actuate the units in the register and the amount is registered on the total register.

As stated the register can be adapted for either decimal or English currency by properly changing the gearing between the driving gear 212 and the registering units and between the units. In the operation of the register the units always rotate in the same direction and not backward consequently each unit is initially turned by operation of its related disk 145.

The subtracting register or meter

When the machine is to be used for postal purposes it is provided with a subtracting register or meter which can be set for the amount for which postage has been prepaid and which register will subtract the value of each stamp printed from the amount set up thereon. And means are provided whereby when the amount of prepaid postage originally set up on the subtracting register is exhausted the machine will become locked.

In the present machine the subtracting register S may be conveniently located below the total register T (Fig. 3). The subtracting register is constructed practically the same as the total register, only it does not require any extra numeral units. The units of the subtracting register are mounted upon a shaft 222, and the numeral disks in the subtracting register are similar to the numeral disk of the total register but are numbered reversely thereto.

In normal raised position each arm 226 engages a slide bar 228 which is normally pressed by a spring 229, but is prevented from being moved by the arms 226 until all of these arms are disengaged therefrom; which can occur only when all the numeral units in the subtracting register have been returned to zero position by the exhaustion of the amount for which the subtracting register was set. When such amount is exhausted and the disks 226 disengage the bar 228 said bar is forced inward by the spring and a rack 230 (Fig. 1) on the bar meshes with a pinion 231 on a shaft 232, disposed below and at right angles to the main shaft 1; and on the inner end of this shaft 231 is mounted a pinion meshing with a segment 233 which is pivoted at 234 on one of the brackets or uprights on which the shaft 1 is mounted. To stud 234 is attached an arm 235 which, when the bar 228 is released actuates the gear 231, will be thrown up into position to engage a stop finger or lock 236 fast on shaft 1, and thus prevent further actuation of the machine until the subtracting register or meter has been re-set for a further amount of prepaid postage. The main shaft is prevented from turning in the reverse direction by means of a dog 240 actuated by a spring 239 engaging a ratchet 238 on the shaft 1.

To prevent unauthorized persons obtaining access to the subtracting register or meter the registers are enclosed in a housing as indicated in Figs. 3 and 36 having a door 242 whose hinge pintles are within the housing and this door may be secured in closed position by a seal or lock which can only be opened by a person having the proper key.

To the hinge rod 241 of the door 242 are attached cam members 243 which engage a slidable bar 245, Fig. 1 carrying teeth slidably mounted in guides 244 and carrying teeth which engage with the pinions in the units of the totaling register so as to lock the same when said door is opened so that the adjustment of the total register cannot be altered when said door is opened. When the door is closed bar 245 is moved outward by the springs thereby freeing the total register for operation by the machine.

In some cases it is desirable to have the subtracting register detachable from the machine, so that it may be removed and taken to the post office for resetting.

A second totaling register (not shown) might be placed within the machine so that if the machine should be operated when the meter is not in position the authorities by comparing the

amount on this second totalizing register with the amounts on the totalizing register in the meter and noting the difference between the readings thereof could determine for what 5 amount of postage the machine has been operated while the meter was detached.

Positioning and locking the main shaft

In the machine shown it is essential that the 10 drum shall be stopped at the end of each rotation with the value printing disks uppermost and underlying the gears 201 with the pinion 36 in exact position to mesh with the respective pinions 201, and as the drum is geared directly to shaft 1 in 15 the ratio of 1:1 means are provided for accurately arresting the shaft 1 at the end of a complete revolution.

In the example shown the shaft 1 is operable 20 manually. Refer to Figs. 12 to 14. On the outer end of the shaft 1 is fixed an arm 294 and upon this arm is slidably mounted extension member 292 which may be slidably connected to member 294 by lugs 293, its movement being limited by pins 295 and 296 on member 294 transfixing slots 25 297 and 298 in the member 292. To the outer end of member 292 is attached a pin 291 carrying a handle 6. When the shaft has made a complete revolution and is in normal position a pin 299 on slide 292 rests upon the upper end of the cam 300, (Fig. 13). Before the shaft 1 can be turned 30 the operator grasping handle 6 must move slide 292 outward until pin 299 clears the stop 300; then the handle and shaft may be rotated clockwise until pin 299 again engages stop 300. To insure that the pin 299 and handle 6 and slide 292 35 will be moved inward sufficiently to cause pin 299 to re-engage stop 300 at the end of revolution a cam 301 (Figs. 12 and 13) is so positioned that pin 299 will engage the upper end of the cam as the pin moves towards the stop 300 and will draw slide 292 inward until the pin is positioned to 40 contact with the stop 300, (Fig. 13).

If the shaft 1 is to be driven by power instead of 45 manually driven, suitable automatic means will be provided for disengaging the pin 299 from the stop at the beginning of an operation.

To prevent the main shaft 1 being turned during the setting operation while shaft 185 is depressed the following devices are employed. A 50 pin 309a on the upper end of a lever 309 projects through a slot in the frame under the end of the cam 301 and against the outer edge of the stop 309 in position to be engaged by the pin 299 if it was attempted to move handle 6 outward 55 and at the beginning of the operation. The arm 309 Figs. 13 and 2, is attached to one end of rock shaft 310 on the other end of which is a finger 311 which is adapted to be engaged by spring pressed dog 313 on a shaft 314 which as previously 60 stated is rocked by depression of the rod 185 as above described. When this rod is depressed the cam arm 312 rocks shaft 310 and arm 309 operates to move pin 309a into position shown in Fig. 13 where it will prevent outward movement 65 of the pin 299 so long as the rod 185 remains depressed. When the rod 185 rises then the shaft is rocked reversely and permits the shaft 310 to rock reversely and permit pin 309a to be moved outward by the pin 299 when the handle is turned 70 out beginning an operation.

From what has been stated it will be seen that the main shaft cannot be turned while the setting up mechanism is being operated but is released after these devices have been set, and 75 also that during the rotation of the shaft the set-

ting devices can not be reset. Depression of rod 185 while the main shaft is being operated can also be prevented by means of a pin which projects into the path of the rod 185, which pin is controlled by a cam on the main shaft and is so positioned as to prevent pressure of the rod 185 until the shaft has made its complete revolution.

To prevent use of the machine by unauthorized persons it might be provided with a lock indicated in dotted lines 317, Fig. 13 which is arranged to prevent outward movement of the pin 299 when the bolt of the lock is projected.

The value printing devices in the drum are all 10 so located in their adjusted positions during the printing of the drum so none of the adjustable 15 parts can be shifted or changed from their adjusted positions during one rotation of the main shaft or one cycle of operations of the mechanisms.

Record strip printing devices 20

In many instances it is desirable to preserve a record of the value of each stamp printed. For this purpose the machine shown is provided with means which at each revolution of the main shaft the value of the stamp printed is also printed upon a record strip or web which may be led into the machine from a roll R located in rear of the setting mechanism. In the example shown a plurality of printing wheels 180 are rotatably mounted upon a shaft 177 (Figs. 2 and 3) supported in brackets on the standards in which the shaft 1 is journaled, and located above shaft 1 and adjacent the upper side of the gears 154. There is a numeral wheel 180 for each gear 154 and each numeral wheel 180 has a pinion 178 25 which meshes with the related gear 154 and the numeral wheels 180 will be adjusted exactly in accord with the value printing wheels 26 in the drum, so that exactly the same numbers will be 30 presented at the printing point by the numeral wheels 180 as are presented at the printing point by the value printing wheels 26.

In the example shown a platen 258 is carried 35 by a bar 257 (Fig. 3) which is attached to radially movable bars 256 and 255 the inner ends of which are slotted to engage and be guided by the shaft 1; and each bar 255, 256 has on its lower end a pin 260 (Fig. 3) engaged by a cam 261 keyed on shaft 1; whereby as the shaft is rotated the bars will be reciprocated, so as to move the platen 50 into contact with the disk 180. The bars can be retracted to move the platen away from the disk 180 by means of springs 259 engaging the shaft 177 fastened to lugs on the bars.

Supported on the framing above the platen is 55 a feed roll 272 (Figs. 1, 2, 3) and a coacting roller 271. On the shaft of roll 272 is an oscillating member 273 carrying a pawl engaging a ratchet on the roll 272, and this member 273 is engaged by the bar 257 on the outward movement of the platen and to cause the pawl and ratchet to 60 operate the roll and advance the record strip R which is first led between the platen and the printing wheels 180, and then between the rolls 272 and 271. After each printing operation the roll is actuated to feed the record strip a proper 65 distance to bring a fresh portion of the strip into position for printing. Preferably the feed roller 272 is made in sections so that the freshly printed record sheets will not be smeared. The printing of the record is effected at each rotation of the main shaft 1, the bar 257 being first moved inward so as to cause the platen 258 to press the strip R against the printing wheels 180 and take 70 an impression therefrom. The printing wheels 75

may be inked by any suitable mechanism. As shown ink is supplied thereto by a roller 268 supported on springs 270. This roller is maintained on a support which may be slid endwise into or out of position through a suitable opening in the casing, and the base of the support being slidably engaged with a guide 269, Fig. 3. Ink is transmitted from roller 268 to the type wheels 180 by a ductor 264 yieldably mounted on one end of oscillating levers 265, pivoted on the shaft 177, and at each rotation of the main shaft 1 the lever 265 is engaged by pins 266 on the rotatable member 145 or 154 so that the roller is first moved into contact with the type wheels 180 to supply ink thereto and then is lowered upon the supply roll 268, so as not to interfere with the setting of the numeral wheels 180.

In the example shown the record strip 4 is led from a supply roll R, and rewound on a roller R', the roll R being supported on shaft 248 and roller R' on shaft 253, see Fig. 3. Any suitable means may be taken for properly actuating the roller R to rewind the record strip. In the machine shown the roller R' is operated for each rotation 25 of the shaft by a member actuated by a bar 271 attached to a lever 276 pivoted on the shaft 182 and having an arm 279, Fig. 2, which engages a cam 278 on the main shaft, said arm being held in contact with the shaft by suitable springs.

30   *Multiple impressions*

In addition to the impression taken on envelopes passed between the drum and impression roller 102 other impressions may be taken from 35 the printing surfaces on the drum during each rotation thereof and the machine shown is provided with means for obtaining two other impressions from such printing surfaces upon webs or strips of paper; which impressions can be used 40 for vouchers, receipts, sales tickets, etc. These devices are indicated at the right hand side of the drum, Fig. 1.

The lower printing mechanism comprises a roller 325a (Fig. 21) on a shaft 324a mounted in 45 levers 321a pivoted at 320a on side plates 318 and 319 of the frame in which the printing mechanism is mounted. Roller 325a is yieldingly pressed toward the drum by springs 326a. One of the levers 321a carries a roller 322a which engages a cam ring 323 on the outer end of the drum 9 (Fig. 2) which is adapted to keep roller 325a out of contact with the periphery of the drum, but permits it to contact with the printing surfaces thereon. A web or strip to be printed 55 is led in to the machine from a roll, not shown, at the rear side thereof through a guide slot 330a (Fig. 39) to and over an angle bar or turner 332a, by which it is deflected at right angles and directed into a guide 331 which is led to the roller 60 325a. After passing between the roller and drum the strip is directed into a guide 328a (Fig. 21) and thence to and between delivery rollers 351 mounted on shafts 334a and 334b in the frame which discharge the web or severed strip directly 65 out of the machine through an opening in the casing adjacent the operating handle 6.

In the example shown (Figs. 1 and 21) another impression roller 325b is arranged above roller 325a and has its shaft 324b mounted on levers 70 321b pivoted at 320b on frame 318, 319, and carrying a roller 322b which engages the cam 323 on the drum to hold roller 325b out of contact with the non-printing surface of the drum.

Roller 325b is yieldingly pressed toward the 75 drum by springs 326b. Another strip or web to

be printed may be led into the machine through a guide slot 333 in rear of the machine and turned over a turner 322b into a guide 331b by which it is directed to and between the roller 325b; thence it is directed into a guide 328b which directs it to and between the rollers 351, and it is delivered with the other strip through the opening at the end of the machine.

The rollers 351 are mounted on shafts 334a and 334b, and on the shaft 334b is a beveled gear 350 10 meshing with a beveled gear 355 on the lower end of an inclined shaft 356, which has a beveled gear 348 on its upper end meshing with a pinion 347 on a shaft carrying a similar pinion meshing with a beveled gear 346 Figs. 1, 2 and 21. 15

The gear 346 is spring actuated upon the completion of each rotation of the shaft to cause it to deliver the web or strips printed by the rollers 325a and 325b at the end of each complete rotation of the shaft 1. In the construction shown 20 the gear 346 is operated as follows; a gear 336 on the shaft 1, Fig. 21 meshes with a pinion 337 on a stud shaft, this shaft having a flange 336 carrying a pawl 329 engaging a ratchet 340 on the hub of a hollow disk 342 within which is a spring 25 which is wound up during the rotation of the shaft 1. As the main shaft completes its revolution the pawl 329 is disengaged from the ratchet 340 by contact with a relatively fixed cam piece or by other suitable means permitting the spring to rotate disk 342 in reverse direction and the gear 345 being connected with the hub of the disk 342 is rotated therewith, and thereby imparts such motion to the rollers 351 as to discharge the paper or strips entered therebetween. Backward rotation of the gear 346 during the winding up of the 35 spring may be prevented by suitable pawl engaging a ratchet 344.

As the several separate imprints are made during one rotation of the drum and from the same 40 printing surfaces they will be absolutely identical. Making three duplicate impressions, one on the envelope and two on separate strips as above described will be useful in many instances. For example, an imprint can be made on an envelope 45 for mailing purposes, a record imprint made on one of the strips can be used for recording purposes in the office, as a registry record etc. and a third imprint on another strip may be used as a voucher or receipt to be given to the customer. 50 The utility of such duplicate impressions or prints would also be useful for other purposes which it is unnecessary to describe herein.

75   *The form inking devices*

In advance of the impression roller 102 is a form inking roller 85, see Fig. 1, is interposed between the impression rollers 325a and 325b Figs. 1 and 21. The roller 85 is mounted in support 90 in which may also be mounted a cooperating 60 distributing roller. The support 90 is mounted on a guide 87 and when inserted in position may be retained by suitable latch, indicated in Fig. 1. The support has a stud 94 on its end by which the support and rollers can be pulled out of the machine when not prevented by the latching strip. The roller 86 and its distributing roller are similarly mounted in a removable frame 95 (Figs 1 and 21) and can be similarly removed endwise from the machine when it is desired for replacement or repair. The inking rollers may be yieldingly pressed toward the drum by springs 88 (Figs. 21 and 22). Access to the printing rollers can be obtained through doors 96 and 97, in the 70 casing, see Fig. 36. 75

The cutting devices

The webs printed by the coaction and operation of rollers 325a and 325b with the drum, may be delivered and rewound, or impressions thereon may be detached if desired. For this purpose any suitable web severing means may be employed. In the machine shown I employ reciprocal knives 358a and 358b (Figs. 1 and 2) which are movable in guides 359a and 359b (Figs. 1, 2, 21, 23) and these knives are pivoted to levers 359c which are linked to a bar 359g (Fig. 2) pivotally connected to the end of a lever 359 which is pulled upward by a spring 357 but is depressed against the action of the spring by a cam 353 on the shaft 1 (Figs. 1 and 2). The cam 353 is so shaped that it will keep the lever 359 down, and thus hold the knives raised, until after the webs have been printed by the coaction of the drum and the impression rollers 325a and 325b. Then the cam releases the lever and the knives are moved down by action of spring 357 severing the ribbon and are operated to deliver the cut printed sections of webs as above described.

Manual receipt

The strip between the rollers 351 may be discharged from the rollers 351 onto a table 390 (see Figs. 37, 31 and 33) so that the operator can conveniently write on registry letters the name and domicile of the consignee. This table is provided with swingable clamps 393a and 393b at each side attached to rock shafts 396a and 396b. These rock shafts are connected by links 395b and 395a which are adapted to be operated by an eccentric 394c on rock shaft 394b which rock shaft can be turned manually by handle 394 (Figs. 31 and 33). After the strips issue from the table, the clamp can be turned back and a carbon sheet interposed between the sheets, the sheets and carbons may then be held in position by the clamps 393a and 393b, and after the operator has written thereon what he desires the clamps can be swung back and the one strip can be lettered by the operator and the other given to the customer.

Means to prevent taking of impressions

It may sometimes be desired to prevent the impression roller 102 making impressions. For this purpose a slide 362 is provided which may be entered between the drum and the periphery of the roller 102 as indicated in dotted lines in Fig. 1. The slide 362 (Figs. 34, 35) may be slidably mounted on base 13 at one side of and at right angles to the table 121, and can be moved in or out by suitable means. As shown it has racks 363a and 363b on its edges (Fig. 34) meshing with pinions 364a and 364b on a shaft 365, and this shaft has a bevel 364c meshing with a bevel 366 on the hub of a pinion 367 fixed on a stub shaft 367a. The pinion 367 meshes with a segment 368 fixed on the lower end of a rod 369 (Fig. 1) which extends out of the casing and has a handle 270 on its upper end by which it can be turned. By turning this rod slide 362 can be moved into, or out of, position between the roller 102 and the drum.

On the shaft 369 is fastened a member 371 (Fig. 2) which engages an arm 372 on a rock shaft 375 which carries arms 376a and 376b which when the shaft is properly rocked will engage the shaft 324b of roller 325b and move said roller away from the drum against the action of the spring 326b, so that while in this position no im-

pression can be made on the strip or web fed between the roller 325b and the drum.

The segment 368 and the member 371 are so angularly positioned on the rod 369 that by turning the arm 369 about one-half revolution slide 362 will be moved forward sufficiently to prevent any imprint being made between the drum and impression roller. The proper turning of rod 369 will cause the member 371 to rock shaft 375 and throw roller 325b out of operative position.

By the arrangement described it will be seen that at will one, two or three impressions can be obtained from the printing devices during each operation of the drum. It will be obvious that if the drum is made sufficiently large still further impressions might be made therefrom by additional printing devices.

The casing

The principal operative mechanisms herein-before described are enclosed in a casing 377 having a base 13 which is mounted upon a bed 14 so as to support the mechanism at the desired elevation. The base 13 is preferably detachably attached to the bed by any suitable means so that the casing containing the operative mechanism can be detached from the base if desired. As shown a plate 18 is attached to a bolt 17 slidably engaged with one end of the bed, see Fig. 1 and normally pressed inward by a spring 16. This bolt can be drawn upwardly manually by its head 15. The plate 18 carries pins 19 which are adapted to pass perforations in the end wall of the base 13, and into corresponding perforations in the end wall of the bed 14 (Fig. 1) and hold this end of the base in position. A similar locking device may be arranged at the other end of the bed, but in this case instead of the bolts 19 the arms 18b of the plate could engage notches in the adjacent end of the base 13 (Fig. 39). The particular base attaching devices form no part of the present invention.

All the operative parts in the machine are protected by the casing 377, Figs. 36, 38 which is suitably fastened to the base in such manner that it can only be removed when the securing devices are opened or unsealed by the persons authorized to do so. This casing is provided with suitable openings or windows indicated in said figures whereby the total register and subtracting register are visible, and also whereby the other proper indicia or parts which should be seen by the operator can be noted. The casing has a window in which the disk 179 can be seen and doors 96 and 97 which can be opened for removing the inking devices, and also has openings 385 and 386 through which access can be had to the plugs of the inking devices of the drum. Also an opening 387 to permit manual adjustment of the data stamps 58. The casting also has a door 63, Figs. 37 and 39 to which access can be had to adjust the dating stamps. This door can only be opened in the position of rest to adjust the drum and when the main shaft has begun its rotation the door will be held closed by means of a dog operated by a cam (Fig. 2) so that the door cannot be opened until the printing drum has been returned to its normal position of rest.

Examples of printing

As stated the printing surface 21 can be made of one or several parts and for any desired matter to be printed thereon in addition to the matter which can be displayed by properly adjusting the various printing devices 26, 36, 51, 25s, Fig. 5.

It will be noted from the foregoing description that the toothed disk 145, cam disk 150, and gear 154 and their interengaging members, constitute a setting up means whereby the register or registers are properly actuated when the main shaft is rotated, and that such setting up means are shifted by adjusting the keys or levers 156. Also that when the parts are in the position shown in Fig. 1 the levers 156 and gears 154 will through the connecting means (194-201, etc.) shift the value printing wheels in the drum in accordance with the value set up by the setting up devices. The pinions 194-201 and their shafts constitute a connecting means between the setting up devices and the value printing wheels when the parts are in the position shown in Fig. 1; in which position the shafts carrying the pinions 194 and 201 have been lowered by the depression of the controlling key 180 on rod 185. After the setting up operation has been performed, the frame carrying connecting means is released, and moves so as to disengage the gears 195 from the related gears 154, and the pinions 201 from the pinions 35 of the value printing wheels in the drum. Then during the next rotation of the main shaft 1, the drum is rotated and the value printing devices operated as described, and the set up devices operate the register in accordance with the value set up.

The adjustment of any lever 156 for any number, say for example 5, will project sufficient teeth 148 on the related setting up unit to engage the related register unit operating devices and shift it 5 points during the next cycle of operations of the machine; and during the said adjusting movement of the lever 156 its related gear 154 (which is at that time in mesh with the related gear 194) will impart rotation through said gear to the pinion 201 and the latter will then be in mesh with the pinion 35 on the related value printing wheel in the drum and shift the latter to present the numeral 5 at the periphery of the drum, so that during the same cycle of operations of the machine that 5 is registered in the register 5 will be printed by the value wheels on the drum. The aforesaid movement of gear 154 also turns the related record printing wheel 180 to present 5 at the printing point, and the number is printed on the record strip during the aforesaid cycle of operations.

On the initial movement of shaft 1, beginning any cycle of operations, the pinions 201 are disengaged from the value printing devices in the drum, and the gears 194 from the gears 154 of the indicating disk 176a (Fig. 1) but these pinions are locked by engagement with the comb 205, Fig. 11 so that there will be no displacement of the gears 194 on pinion 201 while disengaged.

I claim:

- 60 1. In a machine of the character specified, a set of omni-value printing wheels provided with gears, a set of omni-value setting up devices including manually operable levers and gears operated by said levers, a set of laterally movable shafts extending from said gears to said value printing wheels, pinions on said shafts adapted to mesh with the lever actuated gears and other pinions on said shafts adapted to mesh with the value printing gears; means for shifting the shafts to bring the gears thereon into mesh with the value printing gears and the setting gears, whereby the value printing gears may be shifted by said levers, and means for moving said shafts to disengage the gears.
- 75 2. In a machine of the character specified, a

rotary drum, a set of omni-value printing wheels provided with gears mounted in the drum, a set of omni-value setting up devices including manually operable setting gears adjacent said drum, a set of laterally movable nested shafts extending from the said setting gears to the value printing devices, pinions on said shafts adapted to mesh with the setting gears and other pinions on said shafts adapted to mesh with the gears of the value printing wheels, means for laterally moving the shafts to bring the gears thereon into mesh with the setting gears and the value printing gears whereby the value printing gears within the drum may be shifted by said setting gears; and means for moving said shaft laterally to disengage the pinions and gears after the setting operation.

3. In mechanism of the character described, a set of omni-value printing wheels provided with gears, omni-value setting up devices each including a rotatable gear and manually operable means for adjusting said gear, a set of shafts, pinions on said shafts adapted to engage the setting up gears and other pinions on said shafts adapted to engage the gears of the value printing wheel, means for moving said shafts laterally to bring the pinions thereon into mesh with the setting up gears and the value printing gears, and for moving the shafts laterally to disengage the pinions and gears after the setting up operation; and means for taking an impression from the omni-value wheels while the shafts are disengaged from both the setting up devices and the printing wheels.

4. In mechanism of the character described, a rotatable drum, a set of omni-value printing wheels in said drum provided with gears; a plurality of omni-value setting up devices each including a rotatable gear, and manually operable levers for adjusting said gear; a set of laterally movable tubular shafts, pinions on said shafts opposite the setting up gears, and other pinions on said shafts opposite the gears of the value printing wheels; means for moving said shaft laterally to bring the pinions thereon respectively into mesh with the setting up gears during the setting up operation and for laterally moving the shaft to disengage the pinions and gears after the setting up operation; and means for taking an impression from the value wheels while the said shafts are disengaged from both the setting up means and the printing means.

5. In mechanism of the character specified, setting up devices comprising a disk having radially moving teeth, a cam disk engaging said teeth, a manually operable gear, and a radially movable member adapted to lock the toothed disk and gear together and move them rotatorially relative to the cam disk.

6. In mechanism as set forth in claim 5, a set of indicating wheels adapted to be operated by the gear members of the setting up devices.

7. In mechanism as set forth in claim 5, a set of record printing wheels operable by the gear members of the setting up devices; and means for taking an impression from such wheels.

8. In mechanism of the character specified, setting up devices comprising a disk having radially movable teeth, a cam disk mounted concentric with the first disk adapted to control the teeth of the first disk, a gear mounted concentric with the disks, a toothed member adapted to lock the toothed disk and gear together, and a lever connected with the gear for manually operating the latter.

9. In a machine of the character specified, a

rotatable drum, a plurality of independently adjustable printing wheels in the drum each having an actuating gear; a plurality of independently adjustable numeral members adjacent the drum each having an actuating gear, manually operable means and connections for independently adjusting said numeral members; a plurality of parallel shafts exterior to the drum and extending from the numeral members to the drum, spaced 5 gears on each shaft respectively adapted to mesh with a gear on a numeral member and with a gear on the related printing wheel in the drum; means for moving said shafts laterally to bring the gears into mesh when the drum is at rest position 10

15 whereby when the manually operable means are manipulated to set the numeral members the printing wheels will be correspondingly set; means for laterally moving the said shafts to disengage their gears from the printing wheel gears; and means for rotating the drum when the said gears are disengaged to take an impression from the printing wheels.

10. In a machine of the character specified, a rotatable drum; a plurality of printing numeral 25 wheels in the drum arranged on an axis at right angles to the axis of the drum, a gear attached to each printing wheel; a plurality of independently adjustable numeral wheels at one side of and exterior to the drum, a gear attached to each such 30 numeral wheel; a manually operable lever and connections for adjusting the exterior numeral wheels to display any desired value; a set of nested shafts extending from a point adjacent the drum to a point adjacent the exterior set of numeral 35 wheels; gears on said shafts respectively adapted to mesh with a numeral wheel gear and with the related printing wheel gear in the drum; means for laterally moving said nested shafts to bring the gears into mesh when the drum is in rest position 40 whereby when the levers are manipulated to set the exterior numeral wheels the printing wheels in the drum will be correspondingly set; means for laterally moving said shafts to disengage the gears from the printing wheels; and means for rotating the drum when said gears are disengaged to take an impression from the printing 45 wheels.

11. In mechanism of the character described, printing mechanism, consisting of a single printing die unit mounted in a rotary drum and common to a plurality of impression devices, means whereby separate documents may be manually fed to one of said impression devices to be imprinted by said printing die unit, and means whereby a continuous record tape is automatically fed to another of said impression devices to be imprinted by said printing die during a single rotation of said drum.

12. In mechanism of the character described, printing mechanism consisting of a single rotary printing die unit, and a plurality of impression means cooperating therewith, means whereby individual documents may be manually fed to said printing mechanism, or as an alternative, a continuous record tape automatically fed through said printing mechanism.

13. In mechanism of the character described, printing mechanism consisting of a single rotary printing die unit, a plurality of impression feed means cooperating therewith, means whereby individual documents may be manually fed to said printing mechanism in a single direction, and alternative means for automatically feeding a continuous record tape through said printing mech-

anism and impression feed means in the same direction.

14. In a mechanism of the character described a rotary printing drum containing type wheels, means external of said drum, including nested 5 shafts and pinions on said shafts, engaging said type wheels for the setting thereof, such means engaging the said type wheels when the drum is at rest and disengaging therefrom when the drum rotates; means for holding the setting means in 10 locked position when out of engagement with the type wheels, and means for holding the type wheels in locked position when disengaged from the setting means.

15. The combination of independent omni-value set-up means, a rotary drum, means in said drum for printing amounts set up, connecting means between said omni-value set-up means and said printing means including laterally movable shafts and gears whereby the printing means is 20 set by the said set-up means, and means whereby said rotary drum may be rotated to print while said setting up means and said connecting means are inoperative and said connecting means disengaged from both the setting up means and the 25 printing means.

16. The combination of independent omni-value set-up means, a rotary drum, means in said drum for printing amounts set up, connecting means between said omni-value set-up means and 30 said printing means whereby the latter is set by the former, the connecting means including nested shafts and gears thereon and means for laterally moving the shafts to throw the gears 35 into and out of engagement with the set-up means, and the printing means, and means whereby said rotary drum may be rotated to print while said setting up means and said connecting means are inoperative and said connecting means disengaged from both the setting up means and 40 the printing means.

17. The combination of independent omni-value set-up means, a rotary drum, printing means in said drum for printing omni-value amounts, connecting means between said set-up means and 45 said printing means including laterally movable shafts and gears, means for disengaging the said connecting means from both the setting up means and the printing means, and means whereby said rotary drum may be rotated while said setting up 50 means and said connecting means are inoperative and said connecting means disengaged from both the setting up and the printing means.

18. The combination of independent omni-value set-up means, a rotary drum, printing 55 means in said drum for printing omni-value amounts, connecting means between said set-up means and said printing means, the connecting means including nested shafts and gears thereon and means for laterally moving the shafts to throw the gears into and out of engagement with the set-up means and the printing means, means for disengaging the said connecting means from both the setting up means and the printing 60 means, and means whereby said rotary drum may be rotated while said setting up means and said connecting means are inoperative and said connecting means disengaged from both the setting up and the printing means.

19. In a mechanism of the character specified, 70 a rotary printing drum, an impression means cooperating therewith for printing upon individual letters or documents inserted therein, a second impression means for feeding and printing upon tape to be applied to packages or parcels. 75

and means whereby at the will of the operator either of said impression means can be rendered inoperable.

20. The combination of omni-value setting-up devices, a plurality of independent omni-value levers for adjusting the setting-up devices, omni-value rotary printing devices, piece feeding means, tape feeding means, means whereby said rotary printing devices may be adjustably set by said 5 adjustable levers to effect omni-value impressions, means whereby an impression may be taken on individually fed pieces, means whereby an impression may be taken on the tape, and means whereby taking an impression from either may 10 be prevented.

21. In a mechanism of the character specified, a rotary printing drum, a first impression means cooperating therewith for printing upon individual letters or documents inserted therein, a second impression means for feeding and printing upon tape, a third impression means, and means whereby at the will of the operator either of the first or third of said impression means or both 15 can be rendered inoperable.

22. In a machine of the character specified having setting-up devices, a plurality of inde- 20

pendent denominational levers for adjusting the setting-up devices, a manually operable control key, printing devices, and means whereby said printing devices may be adjustably set for printing by said denominational levers only after said control key has been properly shifted; a set of record printing wheels also operable by the setting-up devices in accordance with the value to be printed, and means for taking an impression 10 on a record strip from such wheels.

23. In a machine of the character specified having independent set-up means, a rotary drum, means in said drum for printing amounts set up, connecting means between said set-up means and said printing means whereby the latter is set by 15 the former, and means whereby said rotary drum may be rotated to print while said setting-up means and said connecting means are inoperative and said connecting means disengaged from both the setting-up means and the printing 20 means; a set of record printing wheels also operable by the setting-up devices in accordance with the value to be printed, and means for taking an impression on a record strip from such wheels at each rotation of the drum.

25 MÁRTON KÁLMÁN.
